UNITED STATES PATENT OFFICE

HENRY E. WARREN, OF ASHLAND, MASSACHUSETTS, ASSIGNOR TO GENERAL ELECTRIC COMPANY, A CORPORATION OF NEW YORK

INDICATING MECHANISM

Application filed January 16, 1926. Serial No. 31,817.

My invention relates to indicating mechanism and has for its object the provision of means whereby the position of a moving object and a desired schedule for the moving object may be shown.

More specifically my invention relates to indicating means for objects such as elevators, and the like. In the operation of elevators, it is desirable to have the elevator under the control of a dispatcher in a suitable control station. This is particularly true when a number of elevators are being operated, whereby by having the elevators controlled from a central point the various schedules of the elevators may be correlated and changed to meet the demands in traffic. Furthermore, when an elevator operates at high speeds and at times skips many floors as with express elevators, it is difficult or impossible for the operator on the elevator itself to determine his position by observation of the floors, and it is, therefore, desirable to have position indicating means on the elevator so that the operator can observe his actual position for the purpose of checking it with the desired position determined by the dispatcher. A difficulty in arranging suitable position and schedule indicating means so that they may be easily compared arises from the fact that the elevator has oscillatory motion in upward and downward directions, while it is convenient for purposes of simplicity to indicate the schedule by means of a continuously moving member.

In accordance with my invention I provide schedule and position indicators which move together in substantial coincidence when the elevator is following the schedule. In carrying out my invention in one form, I provide a pair of indicating members for the schedule indicator, these members being driven continuously in opposite directions and being brought into view alternately to indicate the desired upward and downward movements of the elevator, together with a position indicator member moved by the elevator to show its position, this member moving with the schedule indicator member which is in view when the elevator is following the schedule.

For a more complete understanding of my

invention, reference should be had to the accompanying drawing in which Fig. 1 is a fragmentary front elevation view of a position and schedule indicator embodying my invention; Fig. 2 is a side elevation view partly in section of the device shown in Fig. 1; Fig. 3 is an enlarged perspective view showing details of construction; Fig. 4 is a sectional view showing details of construction; while Fig. 5 is a diagrammatic view showing the application of my invention to an elevator.

Referring to Figs. 1, 2 and 3 of the drawing, I have shown my invention in one form as comprising two index hands or pointers 10 and 11 for indicating the schedule, and a single pointer 12 for indicating the position of the elevator. These pointers are mounted to rotate about a common axis and are enclosed in a suitable casing 13 together with driving means therefor. The pointers 10 and 11 are mounted on concentric sleeves 14 and 15 (Fig. 4) secured to driving gears 16 and 17 respectively, which are connected to a suitable driving motor 18. The gear 16 is connected through an idler gear 19 to a gear 20 secured to the shaft 21 of the motor 18, while the gear 17 meshes directly with the gear 22 secured to the shaft 21. It will be observed that the hands 10 and 11 are thus rotated in opposite directions by the driving motor 18. Any suitable driving motor may be used in which provision is made for speed regulation and in which the speed as regulated is maintained with considerable accuracy. The motor 18 is shown and preferably is of the type described and claimed in my Patent No. 1,546,269, dated July 14, 1925.

The position indicator hand 12 is secured to the shaft 23 which is driven through gears 24 and 25 by means of suitable motion receiving motor 26. The motor 26 is operated by the movement of the elevator so that the hand 12 indicates at all times the position of the elevator. It may be of any suitable type, and is preferably of a type having a field winding energized by alternating current such as disclosed in Patent No. 1,551,393 to Hewlett et al., dated August 25, 1925. As shown in Fig. 4, the shaft 23 is rotatably

mounted in the sleeve 15, which in turn is rotatably mounted in the sleeve 14, the latter sleeve being mounted in a suitable bearing in the supporting framework.

5 Referring to Fig. 5, it is contemplated that a schedule and position indicator 27 of the type shown in Figs. 1-3 inclusive will be mounted in the cab 28 of the elevator, a cable 29 providing the electrical connections for the motors 18 and 26. A second schedule and position indicator 30 will be provided in a convenient position for observation by the dispatcher who controls the schedule of the elevator.

15 A transmitting device 31, to which the receiving devices 26 on the indicators are connected, is operated by means of a friction wheel 32 which bears against the cable 33 of the elevator. The transmitting device 31 is electrically connected with the receiving devices by means of the conductors 34. A suitable source of alternating current supply 35 is connected to the field windings of the transmitting and receiving devices by means 25 of conductors 36.

20 The motors 18 of the indicating devices 27 and 30 are operated by means of a suitable source of alternating current having a frequency which can be varied so that the speed 30 of the motors can be regulated. They are shown, for example, as being connected to a rotary converter 37 which is connected to a direct current supply source 38. The field winding 39 of the rotary converter has an adjustable resistance 40 connected in circuit with it across the supply source 38. By varying the amount of the resistance 40, for example, by means of a contact arm 41 co-operating with suitable taps, the speed of 35 the rotary converter can be regulated so as to vary the frequency supplied to the motors 18 in a well known manner. Thus the dispatcher regulates the speed of the motors 18 so that the pointers 10 and 11 indicate the 40 desired speed of the elevator with respect to suitably graduated scale 42 (Fig. 1).

45 It will be observed that the two schedule indicator pointers 10 and 11 will be in coincidence twice each revolution where they pass 50 each other and in the arrangement shown in Figs. 1-3, these pointers pass each other in their two vertical positions when they are pointing upward or downward. A shield or mask 43 is provided in front of the three 55 pointers and this shield has an arcuate slot or opening 44 which is semicircular in extent and terminates on a vertical line passing through the axis of rotation of the pointers. In other words, the slot 44 extends between 60 the points where the pointers 10 and 11 pass each other and is located in one side, shown as the left hand side, of the shield 43. It will thus be observed that the pointers 10 and 11 65 come into view alternately as they pass by the slot 44 and thus indicate alternately the

desired movements of the elevator. While the two pointers actually rotate continuously in opposite directions, the visual effect produced by means of the shield 43 is that of one of a single pointer moving upward and downward with the elevator. The pointer 10 is arranged to move in a counterclockwise direction, and, therefore, moves in a downward direction when in view. It is provided with an arrow 45 which indicates this direction of movement. The pointer 11, which is driven in a clockwise direction, moves in an upward direction when in view and is likewise provided with an arrow 46 indicating this direction of movement.

70 The pointer 12 has a range of movement of 180° corresponding with the travel of the elevator and is arranged to be in view through the aperture 44. In the operation of the elevator the operator on the cab 80 watches the indicator 27 and controls the elevator so as to maintain the pointer 12 substantially in coincidence with that one of the schedule pointers which is in view. The indicator 30 shows the dispatcher how near to 85 schedule the elevator is running.

90 It will be observed that by means of this arrangement the oscillatory movements of the shaft 23, in accordance with the upward and downward movements of the elevator, may be 95 compared with the rotary motion of the shaft 21 under the control of the dispatcher. For convenience the shaft 23 may be termed a "position member" and the shaft 21 may be 100 termed a "schedule member". Obviously the movements of the oscillating position member and the rotating schedule member may be 105 compared in various other ways. For example, the position member 23 may operate a plurality of pointers moving in opposite directions so as to change its oscillatory motion into apparent rotary motion which may then be compared with a single pointer driven by the schedule member 21. Furthermore, the two hands 10 and 11 may be brought into view 110 in various other ways than by the use of the mask 43, for example, by illuminating each hand, as by a beam of light, while it passes over a predetermined portion of the dial.

115 It will be understood that suitable operating mechanism is provided for the elevator; for example, it may be driven by means of an electric motor 47 which is geared to a hoisting drum 48 around which the cable 33 is wound, the cable then passing around an idler wheel 49 and having its end connected to a counter-weight 50.

120 In order to make corrections for any slippage which may occur between the cable and the driving wheel 32 of the transmitting device 31, means are provided for synchronizing the transmitting device each trip of the elevator. A V shaped notch 54 is provided in the periphery of the friction wheel 32 and a V shaped cam 51 is provided on a pivoted arm 125 130

52 in a position to be opposite the notch 54 when the elevator reaches its uppermost position. Just before the elevator reaches this position, a knob 53 on the cable engages the 5 free end of the lever 52 and forces the cam 51 into the notch. The engagement of the cam with the inclined sides of the notch causes the wheel 32 to slip with respect to the cable when necessary and thus brings the wheel into a 10 predetermined position with relation to the cable.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my 20 invention, the scope of which is set forth in the annexed claims.

What I claim as new and desire to secure by Letters Patent of the United States is:

1. A schedule and position indicating system for elevators and the like, comprising a pair of indicating members, means mounting said members for rotation about a common axis, means for driving said members in opposite directions independently of the movements of said elevator, so that said members move alternately in a predetermined path over a predetermined half revolution of their travel, a third indicating member mounted for movement in said path over said half revolution, and means for driving said third member in accordance with the movements of the elevator.

2. A schedule indicator for elevators and the like, comprising a pair of indicating members having predetermined common paths of movement, and means for moving said members in opposite directions alternately over a portion of said predetermined paths at speeds corresponding to the desired 45 upward and downward speeds of the elevator, whereby said members indicate alternately the desired upward and downward movements of the elevator.

3. A schedule indicator for elevators and the like, comprising a pair of indicating members on said elevator, means mounting said indicating members for rotation about a common axis, and means for rotating said members in opposite directions alternately over 55 a predetermined portion of their travel at equal speeds corresponding to the desired speed of the elevator, whereby said members indicate respectively the desired upward and downward movements of the elevator with respect to said predetermined portion of their travel.

4. A schedule indicator for elevators and the like, comprising separate indicating members, means mounting said indicating members 65 below on said elevator in juxtaposition to each

other for indicating the upward and downward movements of the elevator respectively, visual shielding means for said members during a predetermined portion of their travel, and means for driving said members in opposite directions so that said members move alternately over the remaining portion of their travel to indicate the desired upward and downward movements of the elevator.

5. A schedule indicator for elevators and the like, comprising a pair of members on said elevator for indicating respectively the desired upward and downward movements of said elevator, means mounting said members for rotation about a common pivot axis, means for rotating said members in opposite directions at the same speed corresponding to the desired speed of the elevator, and means for obscuring said indicating members alternately during half of each revolution whereby 80 said members move into view alternately during the remaining half of each revolution to indicate the desired upward and downward movements of the elevator.

6. A schedule indicator for elevators and the like, comprising a pair of indicating members, means mounting said indicating members for rotation about a common pivot axis, means for driving said members in opposite directions at the same speed to indicate the 85 desired movements of the elevator, means for varying the speed of said driving means, and a shield for said members provided with an aperture extending between the points where said members are coincident so that said members move into view alternately behind said aperture throughout a given half revolution of their travel to indicate respectively the desired upward and downward movements of the elevator.

7. An indicating device comprising a pair of indicating members, means mounting said indicating members for rotation about a common axis, means for rotating said members in opposite directions, and means 105 for obscuring said members alternately so that said members come into view alternately to simulate a single member having oscillatory motion.

8. An indicating device comprising a pair of indicating members, means mounting said indicating members for rotation about a common axis, means for rotating said members at equal speeds in opposite directions whereby said members move into coincidence each 110 half revolution, and means for obscuring said members over one half revolution whereby said members move into view alternately in the other half revolution to simulate a single member having oscillatory motion.

9. A schedule indicating device comprising a pair of indicating hands, means mounting said indicating hands for rotation about a common axis, a shield for said hands provided with an aperture through which said 120

- hands may be viewed throughout a half revolution, and means for rotating said hands in opposite directions so as to move them before said aperture alternately to simulate a single hand having oscillatory motion. 6
10. A schedule and position indicator for elevators and the like, comprising a position member, a driving connection between said position member and said elevator whereby said member is driven by said elevator in one or the other of two directions in accordance with its upward and downward movements, a schedule member, means for driving said schedule member independently of the elevator, indicator members, means mounting said indicator members in juxtaposition and driving connections between said indicator members and said position and schedule members respectively whereby one of said members is caused to simulate the movement of the other member. 15
11. A schedule and position indicator for elevators and the like, comprising a position member, a driving connection between said position member and said elevator whereby said member is driven by said elevator back and forth in accordance with its upward and downward movements, a schedule member, means for driving said schedule member independently of said elevator, a scale, indicator members cooperating with said scale, and driving connections between said indicator members and said position and schedule members respectively whereby said indicator members show the actual and desired positions of the elevator. 20
12. A schedule and position indicator for elevators and the like, comprising a position member, a driving connection between said member and said elevator whereby said member is driven by said elevator back and forth in accordance with the upward and downward movements thereof, a schedule member, means for driving said schedule member independently of the elevator, indicator members, means mounting said indicator members in juxtaposition and driving connections between said indicator members and said position and schedule members respectively whereby said indicator members move together when the elevator is following the desired schedule. 25
13. A position and schedule indicator for elevators and the like, comprising a position indicator member, a driving connection between said position indicator member and said elevator whereby said indicator member is driven in one or the other of two directions in accordance with the movements of the elevator, a pair of schedule indicator members for indicating the desired upward and downward movements of the elevator, means mounting said schedule indicator members in juxtaposition to said position indicator mem- 30
- ber, and means for driving said schedule indicator members in opposite directions alternately over the path of said position indicator member to indicate the desired position and direction of movement of the elevator. 70
14. A position and schedule indicator for elevators and the like, comprising a pair of indicating members, means for revolving said indicating members at the same speed in opposite directions over a common path, means for obscuring said indicating members alternately during half of each revolution whereby said members move into view alternately during the remaining half of each revolution to show the desired direction and rate of travel of the elevator, a third indicating member mounted adjacent said path so that its movement may be compared with the movement of an exposed indicating member, a driving connection between said elevator and said third indicating member whereby said third member is moved back and forth over said half revolution in accordance with the movements of said elevator. 75
- In witness whereof I have hereunto set my hand this 13th day of January, 1926.
